UNITED STATES PATENT OFFICE.

JAMES R. LEE, OF BALTIMORE, MARYLAND, ASSIGNOR TO THE FIRM OF
TORSCH & LEE, OF SAME PLACE.

DESIGN FOR A BADGE.

SPECIFICATION forming part of Design No. 22,110, dated January 10, 1893.

Application filed November 26, 1892. Serial No. 453,280. Term of patent 7 years.

To all whom it may concern:

Be it known that I, JAMES R. LEE, a citizen of the United States, residing at Baltimore, in the State of Maryland, have invented and produced a new and original Design for Mourning-Badges, of which the following is a specification.

Reference is to be had to the accompanying drawing in which the figure represents a perspective view of a badge embodying my new design.

The leading feature of the design consists in a badge of mourning having a central emblem receiving panel *a* bordered at the top and bottom by contrasting panels *b*, *c*, the said central panel appearing behind, or out of the plane of the end panels, and the whole forming an ornamental framing for an emblem. The minor features of the design con-

sist in the straight converging side lines *e* of the bottom panel *c* and the tassel figure *f*, pendent from the meeting point of such side lines. Further minor features consist in the transverse band figures *g*, *h*, dividing the panel *a* from the panels *b*, *c*, the lower band *g* being curved and having scallops at its lower edge, and the upper band *h* comprising large loops *h'* and alternating straight members *h*².

The badge is surmounted by an ornamental straight bar *j*. 30

I claim:

The design for a mourning badge herein shown and described.

JAMES R. LEE.
